INVENTOR

Ernst Anheuser,
BY
Morsell & Keeney,
ATTORNEY

UNITED STATES PATENT OFFICE.

ERNST ANHEUSER, OF RACINE, WISCONSIN.

FILE OR BRUSH HOLDER.

1,345,472.

Specification of Letters Patent.

Patented July 6, 1920.

Application filed April 12, 1919. Serial No. 289,639.

To all whom it may concern:

Be it known that I, ERNST ANHEUSER, a citizen of the United States, and resident of Racine, in the county of Racine and State of Wisconsin, have invented new and useful Improvements in File or Brush Holders, of which the following is a description, reference being had to the accompanying drawings, which are a part of this specification.

10 The present invention relates broadly to tool holders especially adapted for use in cleaning heavy castings, rubber tire casings, and the like, and has for its primary object to provide a holder capable of receiving files, rasps, brushes or other tools.

Another object of this invention is to provide means for adjustably securing the tool in the holder so that when one portion of the rasp or other tool becomes worn, it may be adjusted to bring the unused portion thereof in contact with the work. This adjustment also permits the engagement of the tool with work at varying heights.

A further object of the invention is to 25 provide an elongated one-piece tool holder of suitable light material having its lower extremity tapered to a point to provide convenient means for preventing the holder from slipping away from the work, and 30 having its other extremity shaped in the form of a handle.

With the above and other objects in view which will appear as the description proceeds, my invention resides in the novel construction, combination and arrangement of parts substantially as hereinafter described and particularly defined by the appended claims, it being understood that such changes in the precise embodiment of the herein 35 described invention may be made as come within the scope of the claims.

In the accompanying drawing, I have 40 illustrated one complete example of the physical embodiment of my invention constructed according to the best mode I have so far devised for the practical application of the principles thereof, in which:

Figure 1 is a plan view thereof, with a portion broken away to show details of construction;

Fig. 2 is a sectional view taken longitudinally through Fig. 1 on the line 2-2.

Fig. 3 is a transverse sectional view taken on the line 3-3 of Fig. 1;

55 Fig. 4 is a plan view of the underneath

side of the novel rasp or file receiver used in connection with my tool holder;

Fig. 5 is a view, part in section and part in elevation of a portion of my holder illustrating a brush connected therewith;

60

Fig. 6 is a view, part in section and part in elevation, said view being taken on the line 6-6 of Fig. 5 and

Fig. 7 is a plan view of the rear face of the plate used to adjustably secure the brush 65 depicted in Fig. 5 to the tool holder.

Proceeding now to the description of the drawing, the numeral 5 designates the holder proper made in one piece and having one end shaped to provide a convenient form of handle 6, and having its other end tapered to form a retaining end or member 7. Throughout the greater portion of the length of the holder is an elongated slot or opening 8. Surrounding the opening of the 70 holder is a flange 9 to provide a guideway for the tool carrying member 10.

Projecting inwardly from the flange 9 on each side of the opening 8 is a rib 11 having steps or lugs 12 formed thereon adapted for 80 engagement in notches 13 in the under side of the tool carrying member 10. The tool carrying member 10 is retained in the frame 5 by means of a transverse plate 14 engaging the outer side of the ribs 11 and held in place 85 by means of a binding screw or wing nut 15 engaging a stud 16 carried by the tool carrying member 10.

From the former description it is obvious that in order to adjust the tool carrying 90 member 10 to various positions on the frame it is merely necessary to unscrew the nut 15 and position the member 10, engaging the lugs 12 and notches 13, and then tighten the nut 15, thus securely fastening said 95 member in place. The tool carrying member 10 is of simple construction, having one end formed with a lip 17 adapted to receive one end of a rasp or file 18, being adjustably secured at its other end by means of a suitable fastening 19 and plate 20 adapted to engage the other end of the tool, thus detachably securing it in its tool carrying member 10.

In Figs. 5, 6 and 7, the tool 18 and the 105 tool carrying member 10 are replaced by a wire brush 21 and holder 22 respectively.

The holder 22 has formed on its outer side a pair of parallel flanges 23 having formed therein notches 24 similar to the notches 13 110

of the tool carrying member 10. The manner of securing the brush 21 and its holder 22 in the frame is identical with that of securing the holder 10 therein.

- 5 In practical use, the work to be cleaned is set upon a lathe or other suitable means for rotating the same, and the rasp or other tool secured in the frame 5 is brought to bear against the work, the tapered portion 7 of
10 the frame being engaged in the floor or other suitable support, as will be readily understood by those skilled in the art to which an invention of this type appertains.

What I claim as my invention is:

- 15 1. A tool holder, comprising an elongated frame, a tool carrying plate movable longitudinally on the frame, and means for securing the plate in adjusted position on the frame.
20 2. A tool holder, comprising a frame member, a tool carrying member, notches being formed in one of said members, lugs

formed on the other of said members for co-operation with said notches, and means for securing the tool carrying member to the 25 frame member.

3. A tool holder, comprising a frame, a retaining member on one end of the frame, a handle on the other end of the frame, a tool carrying member movable on the frame 30 intermediate the retaining member and the handle, and means for adjustably securing the tool carrying member to the frame.

4. A tool holder comprising an elongated frame having a slot therein extending longitudinally for a greater portion of its length, 35 a tool carrying plate movable longitudinally on the frame, and clamping means passed through said slot and connected with said plate and frame for securing the plate in 40 various adjusted positions on the frame.

In testimony whereof, I affix my signature.

ERNST ANHEUSER.
